UNITED STATES PATENT OFFICE.

GEORGE A. MACBETH, OF ALLEGHENY, PENNSYLVANIA.

DESIGN FOR A LAMP-CHIMNEY.

SPECIFICATION forming part of Design No. 14,446, dated November 27, 1883.

Application filed October 10, 1883. Term of patent 14 years.

To all whom it may concern:

Be it known that I, GEORGE A. MACBETH, of Allegheny city, in the county of Allegheny and State of Pennsylvania, have invented a new and original Design for Lamp-Chimneys; and I do hereby declare the following to be a full, clear, and exact description thereof.

My design relates to the tops of lamp-chimneys, its object being to impart to them a neat and attractive finish, and yet preserve for the chimney substantially the appearance of a circular top or edge.

It consists in a lamp-chimney having a flared mouth, and the top or edge beyond said mouth provided with a series of minute scallops extending around it, to impart a neat finish thereto.

My design is illustrated by a side view in the accompanying drawing.

The chimney *a* is provided with the bulged portion *b*, the flared mouth *c*, and the circular edge or top *d*. Extending across said edge are

the minute scallops *e*, these scallops being so small that they do not break the circular outline of the top of the chimney, but by ornamenting said edge do away with the plain appearance of the smooth circular top and add a neat and attracting appearance to the chimney, combining the effect of the ordinary circular plain-finished chimney and the fancifully-finished top.

What I claim as my design, and desire to secure by Letters Patent, is—

The design for lamp-chimneys herein shown and described, consisting in a flared mouth and a top or edge, *d*, provided with a series of minute scallops, *e*, extending around it.

In testimony whereof I, the said GEORGE A. MACBETH, have hereunto set my hand.

GEORGE A. MACBETH.
